UNITED STATES PATENT OFFICE.

WILLIAM ADAM, OF KIDDERMINSTER, COUNTY OF WORCESTER, ENGLAND.

LOOM FOR WEAVING CHENILLE OR FUR PILE FABRICS.

SPECIFICATION forming part of Letters Patent No. 324,287, dated August 11, 1885.

Application filed February 9, 1883. (No model.) Patented in England June 30, 1882, No. 3,087.

To all whom it may concern:

Be it known that I, WILLIAM ADAM, (of the firm of Tomkinson & Adam,) a subject of the Queen of Great Britain, residing at Kidderminster, in the county of Worcester, England, have invented certain new and useful Improvements in Looms for Weaving Chenille or Fur Pile Fabrics, (for which I have received Letters Patent in Great Britain, No. 3,087, dated 30th June, 1882,) of which the following is a specification.

My present invention has for its object improvements on an invention for which United States Letters Patent were granted to me dated 15 August 22, 1882, No. 263,085, and relates, first, to means for insuring the chenille or fur pile being brought up into its proper position. For this purpose I so construct the cam giving the rising and falling motions to the reed 20 as that in the working of the loom extra falling and rising motions shall be imparted to the reed, so as to cause the same to strike the chenille or fur last inserted a second time with the inclined upper ends of the dents, the reed 25 afterward rising in its backward motion to enable the shuttle to go across the loom.

According to the second part of my invention I employ a fixed guide-reed placed as close as possible to the track of the catcher-warp needles, in order to steady the ground-warp threads, and thereby insure the said 30 needles entering their proper spaces between the ground-warp threads.

According to the third part of my invention I so construct the cam giving the rising and falling motions to the catcher-warp needles that the full downward traverse of the said needles is divided into three separate falls, in order to facilitate the setting and 35 holding of the chenille or fur pile as it is being brought into its proper position.

According to the fourth part of my invention, when it is required to insert an extra or a floating warp, I employ, as heretofore, an 45 extra shaft or leaf of healds, but instead of operating such extra shaft or leaf in the manner heretofore adopted, I operate it by means of the other leaves or shafts, or by some of them, according as it is required to raise such extra 50 shaft or leaf at the rise of every heald or at the rise of only certain of them. This I effect

by mounting at the top of such extra shaft or leaf one or more projections capable of being fixed in position by screw or otherwise, so as to extend over some or all of the other shafts 55 or leaves, or over projections therefrom, and thereby cause such extra shaft or leaf to be raised at the rise of every shaft or leaf, or at the rise of only some of them.

And in order that my said invention may 60 be more clearly understood and readily carried into effect, I will proceed, aided by the accompanying drawings, more fully to describe the same.

In the drawings, Figure 1 is a cross section, 65 and Fig. 2 is a sectional side view, of parts of a loom for weaving chenille or fur pile fabrics, showing my present improvements applied thereto. Figs. 3 and 4 are respectively a cross-section and a horizontal section of parts 70 drawn to a larger scale. Fig. 5 is a front view of the loom with certain parts removed in order that other parts may be seen more distinctly; and Figs. 6 and 7 are cross-sections of the loom at different places, showing more 75 particularly the cams for operating the lathe and the healds with their connections.

In all the figures like parts are marked with similar letters of reference.

In the said drawings, my improvements are 80 shown as applied to such a loom as is represented in my said previous Patent, No. 263,085, it being understood that the chenille or fur is inserted in the open shed (formed by the ground-warp-s and the catcher-warp-s) by means 85 of a finger or traverser, which carries the said chenille or fur through that shed from one side of the loom to the other.

a is the main framing. *b* is the first-motion shaft. *c* is the cam or tapped shaft. *d d* are 90 the lathe-swords. *e* is the reed. *f f* are the catcher-warp needles. *g g g* are the shafts or leaves of healds which are operated in the usual way, and *h* is an extra shaft or leaf of healds operated in manner hereinafter described. 95

The reed *e* is operated, as described in the specification of the Letters Patent hereinbefore referred to, and as shown herein at Fig. 1, by cams *e'*, which, by levers *e''* and connecting-links *e'''*, give a downward motion to the reed *e*, while springs *e''''* give the upward mo-

tion thereto. According to such former patent, however, only one fall and one rise were given to the reed at each revolution of the cam e' —that is to say, for each insertion of 5 chenille or fur—but according to the first part of my present invention I so construct the cam e' that it shall impart two falls and two rises to the reed e at each revolution of the said cam. This construction is shown in Fig. 1 10 of the drawings, where the cam e' is represented as being provided with two falling grades, $s' s^2$, and with two rising grades, $t' t^2$, which grades operate upon the truck of the lever e^2 in the manner in which cams usually 15 act upon their levers. By constructing the cam e' as shown in the drawings I cause the reed e , as described in my said former specification, first, to strike the last-inserted chenille or fur with the inclined faces of the upper 20 ends, e^* , of the reed e , (that is, when down,) and then to rise so as to stroke up the chenille or fur pile. The reed e retires from the fell of the work in this position, and then in again 25 coming forward it is caused, according to my present invention, to fall, and again to strike the chenille or fur pile with the upper ends, e^* , after which it again rises as it recedes, to enable the shuttle to run across the loom. The reed e then falls and again strikes the work 30 when down, after which it remains down, while the lathe goes back to rest, in which position of such parts—that is, when the lathe is back and the reed down—the fur or chenille is carried across the loom. By thus causing 35 the reed to strike the chenille twice the portions of the fur pile which have not been struck up by the first blow of the reed are acted upon by the second blow thereof, and consequently the fur pile is struck up with 40 much greater uniformity than is practicable when it is operated upon but once by the reed.

The means which I prefer to use to operate the lathe when the reed is moved, as above described, are represented more particularly 45 in Figs. 5 and 6. Each sword d of the lathe is connected by means of a toggle-link, d' , with an arm, d^2 , which is fitted to vibrate freely upon the first motion-shaft b . Each of these links d' is operated by a cam, d^3 , secured 50 to the cam-shaft c , the cam operating upon the link through the intervention of the truck d^4 , lever d^5 , and rod d^6 , which last is, by preference, made adjustable, as represented in 55 said drawings. The grades d^7 of the lathe-cams d^3 are constructed, as represented in said Fig. 6, so as to raise and depress the respective toggle-links d' , and thus move the lathe forward and backward. As the cam-grades d^7 occupy only a part of the periphery of the 60 lathe-cams d^3 , the lathe remains at rest during a part of each revolution of the cams—that is, after the last cam-grade in the series has operated until the first cam-grade is brought around to the lever-truck d^4 .

65 According to the second part of my present invention I employ a fixed guide-reed, i , as shown, placed as close as possible to the track

of the catcher-warp needles $f f$, and of the same gage as the latter in order to steady the ground-warps, and thereby insure the said 70 needles entering their proper spaces between the ground-warp threads.

According to the third part of my present invention I divide the full downward traverse of the catcher-warp needles $f f$ into three 75 separate falls and dwells, in order to facilitate the setting and holding of the chenille or fur as it is being brought into its proper position. For this purpose I employ, as described in my 80 said former specification and as shown in the accompanying drawings, a cam, here lettered f' , which, by a lever, f^2 , connecting-rod f^3 , and lever f^4 , gives the rising and falling motions to the catcher-warp needles $f f$; but instead of giving merely one rising and two falling 85 motions to such catcher-warp needles $f f$ in the full extent of their traverse, I construct the cam f' , as shown at Fig. 2, with three 90 grades, so as to divide the full downward traverse of the catcher-warp needles $f f$ into three 95 separate falls, the first of which is determined by the grade 1*, and carries the catcher-warp needles $f f$ down to the position marked 1, Fig. 3—that is, sufficiently far 100 to enable the catcher-warps to hold the chenille or fur—and to remain in such position while the latter is being adjusted, and yet permit the weaver readily to draw the selvage-thread from under and beyond, so as to place it outside the chenille or fur when the latter 105 is turned at the selvage. The second fall is determined by the cam-grade 2*, and carries the catcher-warp needles $f f$ down to the position marked 2, Fig. 3—that is, sufficiently far 110 for the catcher-warps to securely hold the chenille or fur in its adjusted position—in which position the catcher-warp needles $f f$ remain while the chenille or fur is being beaten and stroked up. The third fall is determined by the cam-grade 3*, Fig. 3, and carries the 115 catcher-warp needles $f f$ down to the position marked 3 in Fig. 3—that is, to the bottom of the shed—where they remain sufficiently long to enable the shuttle to be thrown across the loom the required number of times to bind 120 the catcher-warps, and consequently the chenille or fur. They then again rise and return to the position marked 0, where they remain while the chenille or fur is being carried across 125 the loom.

According to the fourth part of my present invention, when it is required to insert an extra or a floating warp I employ, as heretofore, an extra shaft or leaf, h , of healds; but instead of operating such extra shaft or leaf h in the manner heretofore adopted I operate it by means of the other leaves or shafts $g g g$, or by some of them, according as it is required to raise such extra shaft or leaf h at the rise of every heald $g g g$, or at the rise of only certain of them. This I effect by fitting the upper bar of such extra shaft or leaf h with one or more projections or studs, h' , Fig. 3, capable of being fixed in position by screw or oth-

erwise, so as to extend over some or all of the other shafts or leaves $g g g$, or over projections therefrom, and thereby cause such extra leaf or shaft h to be raised at the rise of every shaft ; or leaf $g g g$, or at the rise of only some of them. The means by which I prefer to operate the said leaves or shafts g are represented more particularly in Figs. 5 and 7 of the drawings, each leaf g being operated by an appropriate cam, g' , through the intervention of a truck, g^2 , lever g^3 , rod g^4 , and overhead lever g^5 , from the inner end of the last of which the leaf is suspended. The cams g' , two of which are shown in the drawings, are secured 10 to the cam-shaft c . I have used and have described cams for operating the reed, the catcher-warp needles, and the shafts of the ground-warp threads, but equivalents for these may be used for the same purpose.

Having thus described the nature of my said invention, and the mode in which I carry the same into effect, I would have it understood that what I claim is—

1. The combination, substantially as before set forth, of the reed of the loom with cams constructed with two falling grades and two rising grades, whereby two falls and two rises are imparted to the reed for each insertion of the chenille.

2. The combination, substantially as before set forth, of the cams e' , constructed and op-

erating as described, with the levers e^2 , connecting-links e^3 , springs $e^4 e^4$, and reed e .

3. The combination, substantially as before set forth, of the catcher-warp needles with the 35 guide-reed, which is set close to the track of said needles so as to steady the ground-warp threads and insure the entrance of said needles in the spaces between said ground-warp threads.

4. The combination, substantially as before set forth, of the catcher-warp needles with a cam constructed with three grades, whereby the descent of the said needles is divided into three falls, substantially as described.

5. The combination, substantially as before set forth, of the cam f' , constructed with three cam-grades, the lever f^2 , connecting-rod f^3 , lever f^4 , and catcher-warp needles ff .

6. In combination with the leaves or shafts $g g g$ of healds, the extra leaf or shaft h , and projection or projections h' , extending over and operated by some or all of the leaves or shafts $g g g$ or by projections therefrom, substantially as herein shown and described, and for 55 the purpose stated.

WILLIAM ADAM.
